UNITED STATES PATENT OFFICE.

KARL BORSCHUTZKY, OF HERBESTHAL, GERMANY.

COMBINED DREDGING AND RAMMING DEVICE.

1,132,510.

Specification of Letters Patent. Patented Mar. 16, 1915.

Application filed March 19, 1914. Serial No. 825,906.

To all whom it may concern:

Be it known that I, KARL BORSCHUTZKY, architect, a subject of the King of Prussia, residing at Herbesthal, Rhineland, in the 5 Kingdom of Prussia, Empire of Germany, have invented a new and useful Combined Dredging and Ramming Device; and I do hereby declare the following to be a full, clear, and exact description of the invention, such as will enable others skilled in the art to which it appertains to make and use the same.

This invention relates to a combined dredging and ramming device for making 10 ditches and shafts with an inclosing mantle, and the object of this invention is to provide a device of the character stated, with which the blows of the ram-block are transmitted to the pile-planking or such like serving as 15 shaft-mantle, by means of an anvil which is formed so as to allow the dredging engine to pass through it freely. As the frame of the dredger is freely guided through the said anvil, the dredging device may be adjusted in height independently of the mantle and the ramming device.

The invention is illustrated on the accompanying drawings, in which:

Figure 1 is a longitudinal section through 20 a combined dredging and ramming installation, Fig. 2 is a similar longitudinal section but in a plane at right angles to the section according to Fig. 1, Fig. 3 is a longitudinal sectional view of a modification, Fig. 4 is a 25 cross-section taken on line A—B of Fig. 2, Fig. 5 is a cross-section taken on line C—D of Fig. 3.

As is to be seen with reference to Figs. 1, 2 and 4 the iron mantle *a* which prevents 30 the breaking in of the sides of the ditch is provided with supporting shoulders *b* which serve as stops and supports for the anvil *c*.

The frame of the dredging device consists 45 of pipes *d* which extend within the mantle from top to bottom. These pipes are open at their lower ends and provided with connecting-pipes *e* at their upper ends so as to be adapted for connection to the suction-pipe of a pump, thus serving as a suction-dredger. The pipes *d* are provided near 50 their upper and lower ends with suitable bearings in which the shafts *g* of the dredger-drums *f* are mounted. Chains *h* are passed around these drums and the buckets *i* are fastened to these chains.

The anvil *c* is provided at transversely op-

posite points with recesses *k* which are so formed as to allow the chains and buckets of the dredger to freely pass through them. Besides, the anvil has vertical bores *l* in 60 which the pipes *d* are loosely guided; owing to this arrangement the dredging device may be adjusted in height independently of both the mantle and the ramming device.

According to Figs. 1 and 2 the ram-block 65 *m* is operated by hand. In order to deaden or dull the hard strokes of the ram-block a spring *n* may be inserted between the ram-block *m* and the anvil *c*, as illustrated in Figs. 1 and 3.

According to Figs. 3 and 5 the mantle *a* consists of a number of concrete rings which are connected with each other by means of iron rods *o*. For ramming the pile-planking in this case a ram *m* operated by steam 70 or compressed air is employed, which may also be used with the form shown in Figs. 1 and 2. The moving fluid is fed through pipe *p* and led off again by pipe *q*. If the ditch is made deeper and the mantle becomes too short by reason of this and the dredging device because of the constant discharging of the excavated material both devices may be prolonged at the top by means of suitable lengthening pieces.

The combined dredging and ramming device can be used in any firm or loose ground as well as in water. It serves preferably for making well-shafts and foundation-ditches or trenches for pillars, in which latter case the iron piling may be extracted again when filling up the ditch with concrete.

Having thus described my invention, what I claim as new and desire to secure by Letters Patent is:

1. In a combined dredging and ramming device, an anvil, a ram-block arranged above the anvil, this anvil being provided with means permitting the free passage of the 100 dredger with its buckets, and means for guiding the frame of the dredging device through the anvil and transmitting the blows of the said ram-block to the shaft-mantle.

2. In a combined dredging and ramming device, an anvil, a ram-block arranged above the anvil, this anvil being provided at transversely opposite sides with recesses permitting the free passage of the dredger with its 110 buckets, and means for loosely guiding the frame of the dredging device through the

anvil and transmitting the blows of said ram-block by means of the anvil to the shaft-mantle.

3. In a combined dredging and ramming device, an anvil, a ram-block arranged above the anvil, this anvil being provided at transversely opposite points with recesses for the free passage of the dredger, and having suitable bores loosely guiding the frame of the dredger, and means for transmitting the blows of said ram-block by the aid of the anvil to the shaft-mantle.

4. In a combined dredging and ramming device, an anvil, a ram-block arranged above the anvil, this anvil being provided at transversely opposite sides with recesses for the

free passage of the dredger, and having suitable bores through which the frame of the dredger is loosely guided, and a shaft-mantle provided with inwardly projecting shoulders, these shoulders supporting the anvil and transmitting the blows imparted to them by the ram-block to the shaft-mantle. 20

In testimony whereof I have signed my 25 name to this specification in the presence of two subscribing witnesses.

KARL BORSCHUTZKY.
